FOAM-MAKING PUMP

James C. Hesson, Riverdale, Ill., assignor to Cardox Corporation, Chicago, Ill., a corporation of Illinois

Application July 9, 1956, Serial No. 596,554

6 Claims. (Cl. 103—136)

This invention relates to new and useful improvements in pumps and deals more particularly with vane type pumps for delivering large quantities of fluid at relatively low pressures.

The mass application of mechanical foam, formed of water, a foam stabilizer and air, is widely used for the extinguishment of certain types of fires. It is also well known that the production and delivery of such foam can be accomplished with a vane type pump, the intake of which is flooded by the controlled admission thereto of the liquid ingredients of the foam in the desired proportions. The quantity of liquid admitted to the pump is less than the actual displacement of the pump, however, and the balance of the displacement is made up of air which is drawn into the intake of the pump through an open air inlet along with the liquids. The liquids and air are thoroughly churned within the pump and the resulting foam is homogenized while passing through a series of screens in a stabilizing chamber at the outlet of the pump.

Certain operational difficulties have been encountered in the past in connection with the use of vane type pumps as described above. For example, the inlet and outlet ports of the pump housing must be large if the pump is to operate properly. This means that the vanes moving across the ports will be retained against radial outward movement by a very limited engagement between their outer edges and the inner surface of the housing. The engaged portions of the vanes and housing at the inlet and outlet ports, therefore, are subjected to excessive and nonuniform wear and the irregularities thus formed in the edges of the vanes will reduce the efficiency of the pump and may result in breakage of the vanes after a relatively short period of use.

A further problem encountered in the use of vane type pumps results from the accepted practice of having the eccentricity between the vane rotor and the inner surface of the housing so arranged that the vanes are moved to a position of minimum radial extension just as they move past the outlet port. During movement of the vanes from the outlet to the inlet port, therefore, the vanes are moving radially outwardly and the volume of the space formed between each two adjacent vanes is increasing. This creates a vacuum in each such space during a portion of each revolution of the pump rotor and increases the power required to operate the pump.

It will also be appreciated that any increase in the churning action or turbulence created within the pump adds materially to the effectiveness of the pump as a foam producing device.

It is the primary object of this invention to provide a vane type pump that is so constructed as to minimize wear of the vanes and produce a maximum quantity of foam per unit of power supplied to the pump.

A further important object of the invention is to provide such a pump which will substantially eliminate any pressure differential acting on opposite sides of the vanes

2

approaching the inlet of the pump so that the pump will operate without unnecessary drag on the rotating parts thereof.

Another important object of the invention is to provide the above mentioned type of pump with relatively large inlet and outlet ports, and to support the vanes during their movements across said ports in such a manner as to prevent nonuniform or excessive wearing of the outer edges of the vanes.

Still another object of the invention is to provide a vane type pump wherein the foam forming material passing through the pump is subjected to the churning action of a relatively high velocity spray before its release at the outlet port of the pump.

Other objects and advantages of the invention will be apparent during the course of the following description.

In the accompanying drawings forming a part of this specification and in which like reference characters are employed to designate like parts throughout the same,

Figure 1 is a longitudinal sectional view of a pump embodying the invention.

Figure 2 is a transverse sectional view taken on line 2—2 of Fig. 1.

Figure 3 is a front elevational view, partly broken away, of the pump housing,

Figure 4 is a fragmentary sectional view taken on line 4—4 of Fig. 3,

Figure 5 is a top plan view, partly broken away, of the housing illustrated in Fig. 3, and

Figure 6 is a single plane projection of the cylindrical inner surface of the pump housing showing the positions of the inlet and outlet ports of the housing.

In the drawings, wherein for the purpose of illustration is shown the preferred embodiment of the invention, and first particularly referring to Figs. 1 and 2, it will be seen that the pump housing 7 is chambered to provide a cylindrically shaped inner surface 8. The housing 7 also is provided with an inlet passage 9, which is arranged tangentially of its bottom portion, and an outlet passage 11, which extends vertically upwardly from the upper portion of the housing. The inlet passage 9 opens into the chambered interior of the housing 7 through an inlet opening 12 and the outer end of the inlet passage communicates with an inlet manifold 13 which is mounted on the housing 7. In the upper portion of the inlet manifold 13 there is provided an air inlet passage 15 which opens to the atmosphere through a screen 16. Liquid is admitted to the inlet manifold 13 through a hose adapter 17 which is mounted on the opposite side of the manifold from the inlet passage 9. An open drain port 18 is provided in the bottom of the inlet manifold 13 for communication with the outer end of the inlet passage 9 through the horizontally arranged passageway 18a.

The outlet passage 11 opens into the chambered interior of the housing 7 through an outlet opening 19 and the upper end portion of the passage has mounted therein a plurality of screen discs 20 through which the material discharged from the pump must pass. At its outer end portion, the outlet passage 11 communicates with an outlet coupling 21 which is mounted on the housing 7 for connecting the pump to a discharge pipe, or the like, not shown.

End plates 22 and 23, see Fig. 1, are mounted on opposite ends of the housing 7 and are provided with eccentrically arranged hub portions 24 and 25, respectively, for receiving the axially aligned, antifriction bearing units 26. These bearing units rotatably support a longitudinally extending shaft 27, one end portion of which extends beyond the end plate 22 and through the cap 28 that is mounted on the hub 24 and the other end portion of which extends beyond the end plate 23 and into a gear

casing 29 that is mounted on the housing 7 outwardly of the end plate 23.

Keyed to the shaft 27 between the end plates 22 and 23 is a cylindrically shaped rotor 31 having five longitudinally extending, radial, webs 32 arranged at equally spaced points between and connecting the peripheral portion 33 of the rotor and the hub 34 thereof. Both the peripheral portion 33 and the hub 34 have their opposite ends positioned in closely spaced relationship with the opposed inner surfaces of the end plates 22 and 23. Seal assemblies 35 are provided at opposite ends of the hub 34 to prevent the flow of liquid between the ends of the hub and the associated inner surfaces of the end walls 22 and 23. If, however, any liquid escapes past the seal assemblies 35, this liquid will encounter the slinger rings 36 and 37, mounted on the shaft 27 between the end plates 22 and 23, respectively, and their associated bearing units 26, and will be thrown radially outwardly into the channels 38 that are formed in the end plates. Any liquid entering the channels 38 will flow downwardly through the channels and will be released through the ports 39.

Formed in each web 32 of the rotor 31 is a longitudinally extending, radially outwardly opening slot 41; the slots of circumferentially successive webs having fitted therein vanes 42a, 42b, 42c, 42d and 42e. These vanes are freely movable in a radial direction in their associated slots 41 and it will be readily apparent that rotation of the rotor 31 will cause the centrifugal forces acting on the vanes to maintain the outer edges of the latter in sliding engagement with the inner surface 8 of the housing 7.

That end portion of the shaft 27 which extends beyond the end plate 23 into the gear casing 29 has keyed thereto a gear 43 which is arranged in meshing relationship with a pinion 44. This pinion is keyed to a stub shaft 45 which is rotatably mounted in the gear casing 29 and one end portion of which projects outwardly therefrom for driving connection with any suitable prime mover, not shown. Rotation of the shaft 45, therefore, will cause the pinion 44 to rotate the gear 43 and its attached shaft 27 to impart rotary movement to the rotor 31 within the chambered interior of the housing 7.

By reference to Fig. 2, it will be readily apparent that the eccentric arrangement of the shaft 27 relative to the inner surface 8 of the housing 7 is such that the peripheral surface of the rotor 31 lies in closely spaced relationship with the inner surface of the housing at the departure side of the outlet opening 19 in accordance with the direction of rotation of the rotor, as indicated by the arrow A. In other words, the space between the peripheral surface of the rotor 31 and the inner surface 8 of the housing 7 expands in the direction of rotation of the vanes 42a to 42e from a minimum clearance at the line marked 0° in Fig. 2 to a maximum clearance at the diametrically opposed line marked 180° in Fig. 2 and contracts from this 180° line to the 0° line. It will also be apparent that the volume of each chamber defined by the peripheral surface of the rotor 31, the inner surface 8 of the housing 7 and each adjacent pair of vanes 42a to 42e increases from a minimum value, when the chamber is centered on the 0° line, to a maximum value, when the chamber is centered on the 180° line, and decreases from the maximum to the minimum value during the remaining one-half revolution. Of course, while a chamber is passing the 0° line, the portion of the chamber on one side of the line is increasing in volume and the portion on the other side of the line is decreasing in volume, the two portions being separated from each other by the 0° line of minimum clearance between the rotor 31 and the inner surface 8 of the housing 7.

Referring now to Figs. 3 to 6, inclusive, for a detail description of the pump housing 7, it will be noted that

the inlet passage 9 and outlet passage 11 are shorter than, and are centered longitudinally of, the inner surface 8 so that the opposite end portions of the inner surface are circumferentially continuous for uninterrupted engagement with the opposite end portions of the outer edges of the vanes 42a to 42e to limit radial movement of the vanes in the slots 41. Circumferentially spanning the inlet opening 12 are a pair of vane retaining bars 46 which converge from the circumferentially continuous end portions of the inner surface 8 toward the center of the housing 7 in the direction of rotation of the vanes 42a to 42e.

The bars 46 are symmetrically arranged relative to the circumferentially extending center line of the inner surface 8 and the inner surfaces 47 of the bars are longitudinally aligned with and form a continuation of the inner surface 8 across the inlet opening 12. As is best illustrated in Fig. 4, the sides of the bars 46 facing outwardly from the chambered interior of the housing 7 are tapered to minimize any resistance to the flow of fluids into the chambered interior of the housing past the bars.

Centered longitudinally of the inlet opening 12 is a vane retaining tongue 48 which projects circumferentially from the approach side of the inlet opening. The inner surface 49 of the tongue 48 is also aligned with the inner surfaces 47 of the bars 46 and the inner surface 8 of the housing. It will be readily apparent, therefore, that the vanes 42a to 42e moving past the inlet opening 12 will be continuously supported at the opposite end portions of their outer edges by the inner surface 8 of the housing and the intermediate portion of the outer edges of the vanes will be supported first by both the inner surface of the tongue 48 and the inner surfaces 47 of the bars 46 and subsequently, by the converging inner surfaces 47 of the bars 46 so that any wear produced by the engagement of the vane edges with the tongue and bars will be uniformly distributed along the lengths of such edges.

Formed in the inner surface 8 of the housing 7 are a pair of vacuum relief grooves 50 which are aligned with the spaces formed between the opposite sides of the tongue 48 and the bars and extend circumferentially from the approach side of the inlet opening 12. In other words, the circumferential length of the grooves 50 is such that they open radially inwardly into substantially all of the diverging space between the rotor 31 and the inner surface 8 on the approach side of the inlet opening 12.

Extending circumferentially across the outlet opening 19 are a pair of vane retaining bars 51, which are angularly arranged to converge from the approach side to the departure side of this opening. It will be noted that the bars 51 are symmetrically arranged with respect to the circumferentially extending center line of the inner surface 8 and that the inner surfaces 52 of the bars are longitudinally aligned with and provide a continuation of the inner surface 8 of the housing 7.

Formed in the inner surface 8 of the housing 7 at the approach side of the outlet opening 19 are two grooves 53, see Figs. 5 and 6, which diverge radially and circumferentially from a point that is spaced approximately 90° from the inlet opening 12 to the adjacent side of the outlet opening. It will be noted in Fig. 6 that the portions of the inner surfaces 52 of the outer ends of the bars 51 extend into the grooves 53 and that the portion of the inner surface 8 between the two grooves forms a triangular vane supporting area 54. It will be readily apparent that the outer edges of the vanes 42a to 42e moving across the outlet opening will be supported against radial outward movement by the circumferentially continuous end portions of the inner surface 8 and, during their approach to the opening, by the triangular area 54 of the inner surface 8 and by the aligned end portions of the inner surfaces 52 of the bars 51. Further, during their movement across the outlet opening 19, the vanes

42a to 42e are supported by the converging inner surfaces 52 of the bars 51 so that any wear on the outer edges of the vanes, due to their engagement with the bars, will be uniformly distributed across those portions of the vanes extending between the circumferentially continuous end portions of the inner surface 8.

Referring once again to Figs. 1 and 2 for a detail description of the operation of the invention, the pump is operated by a prime mover which rotates the shaft 45 and the pinion 44 mounted thereon. This rotation of the pinion 44 will effect rotation of the gear 43 and its connected shaft 27 to cause the rotor 31 and the vanes 42a to 42e carried thereby to be rotated within the eccentrically related chamber in the housing 7. Rotation of the rotor 31 will cause the outer edges of the vanes 42a to 42e to be urged into sliding frictional engagement with the inner surface 8 of the housing 7 by the centrifugal forces acting thereon. When the pump is operating, a properly proportioned mixture of water and a foam stabilizing agent is admitted through the adapter 17 to the inlet manifold 13 to flood the inlet passage 9. The quantity of liquid introduced through the inlet manifold 13, however, is less than the displacement of the pump so that a certain amount of air is drawn into the inlet manifold through the screen 16 and the air inlet passage 15 for mixture with the liquids entering the inlet passage 9 of the pump.

By reference to Fig. 2, it will be readily apparent that the chamber defined by the peripheral surface of the rotor 31, the inner surface 8 of the housing 7 and each adjacent pair of vanes 42a to 42e increases in volume as the leading vane passes the position of minimum clearance between the rotor and the inner surface and continues to increase until the center of the chamber reaches a point diametrically opposite the position of minimum clearance. The chamber will thereafter decrease in volume until the trailing vane of the chamber has moved across the outlet opening 19. The mixture of air, water and foam stabilizing agent, therefore, is drawn into the above described chamber by its increase in volume and is forced from the chamber into the outlet passage 11 by the subsequent decrease in its volume. Of course, the mixture of air, water and foam stabilizing agent is subjected to a great deal of turbulence during its movement through the pump and the foam produced by this turbulence is homogenized and stabilized as it flows through the outlet passage 11 and the screen discs 20 into the outlet coupling 21.

Referring now to Fig. 6 for a detail description of the manner in which the outer edges of the vanes 42a to 42e cooperate with the inner surface 8 of the housing 7 during operation of the pump, it will first be noted that the position of minimum clearance indicated by the 0° line of Fig. 2 is also indicated by the 0° line of the projected inner surface 8 illustrated in Fig. 6. Further, the projected inner surface 8 extends from the 0° line in the direction of rotation of the vanes 42a to 42e, as indicated by the arrow A, and the line of contact between the outer edge of each vane and the inner surface 8, when the vanes are positioned as illustrated in Fig. 2, is shown by broken lines in Fig. 6 and identified by the reference characters of the vanes. Due to the eccentric relationship between the axis of the rotor 31 and the axis of the cylindrical inner surface 8, the spacing between adjacent lines of engagement of the outer edges of the vanes 42a to 42e and the inner surface 8 varies as the vanes are rotated, the minimum spacing occurring when the vanes are at equal distances on opposite sides of the 0° line and the maximum spacing occurring when the vanes are spaced at equal distances on opposite sides of the 180° line.

Fig. 6 also illustrates the portions of each revolution of the vanes 42a to 42e during which fluid is taken into each chamber and during which fluid is exhausted from

each chamber. Both of these portions of a revolution are related to the position of the leading vane of a pair. In other words, fluid is being admitted to the chamber behind a given one of the vanes 42a to 42e during movement of the that vane through that portion of a revolution labeled "Intake" in Fig. 6 and is being forced from the chamber during movement of the vane through that portion of the revolution labeled "Exhaust." It will be noted that the "Intake" and "Exhaust" portions of each revolution overlap while a chamber moves past the 0° line so that fluid is being drawn into the portion of the chamber on one side of such line at the same time that fluid is being forced out of the chamber on the other side of the line. It will also be noted that a slight amount of clearance is provided between the "Intake" and "Exhaust" portions of a revolution as the chamber passes from communication with the inlet opening 12 into communication with the grooves 53 so that fluid cannot pass directly from the grooves to the inlet opening.

Considering now the movement of a given one of the vanes 42a to 42e along the surface 8 from left to right, as viewed in Fig. 6, and recalling that the space between the rotor 31 and inner surface 8 expands from the 0° line to the 180° line, it will be readily apparent that as a vane moves into radial alignment with the grooves 50 fluid will be drawn from the inlet opening 12 through the grooves and into the space between the vane and the 0° line due to the increasing volume of the space. This flow of fluid through the grooves 50 will prevent the formation of a vacuum behind the vanes 42a to 42e as they approach the inlet opening 12 and will thereby eliminate any pressure differential on opposite sides of the vanes which would tend to resist rotation of the rotor 31.

As the selected one of the vanes 42a to 42e continues its movement along the grooves 50, the next successive vane will move past the 0° line and the chamber between these two vanes will continue to increase in volume so that additional fluid will be drawn into the chamber while the leading vane moves across the inlet opening 12. During the movement of each vane across the inlet opening 12, it will be supported against radial movement by engagement with the uninterrupted end portions of the inner surface 8 and by engagement first with the inner surface 49 of the tongue 48 and subsequently with the angularly converging inner surfaces 47 of the bars 46. The total area of engagement between the vanes and these supporting surfaces, therefore, is sufficient to prevent undue wear on the vanes and that wear which does occur along the outer edges of the vanes will be uniformly distributed to prevent the formation of any irregularities which might permit leakage of fluids past the vanes.

The trailing one of a selected pair of vanes 42a to 42e will move past the inlet opening 12 just prior to movement of the leading vane of such pair into alignment with the grooves 53 which communicate with the outlet opening 19. When the leading vane moves into alignment with the grooves 53, therefore, no fluid will be permitted to flow from the outlet opening 19 to the inlet opening 12 and the converging relationship between the rotor 31 and the inner surface 8 will cause the fluid to be expelled through the grooves 53 and subsequently through the outlet opening 19 into the outlet passage 11. This expulsion of fluid will continue until the trailing vane of the selected pair has moved past the outlet opening 19.

During movement of the vanes 42a to 42e across the outlet opening 19 they are supported by engagement between their outer edge portions and the uninterrupted end portions of the inner surface 8 and by engagement with the converging inner surfaces 52 of the bars 51 so that the vanes will be subjected to a minimum amount of wear and the wear which does occur will be uniformly distributed across the width of the vane as was previously described in connection with the inlet opening 12.

Since the pressure of the fluid in the outlet passage 11

will be somewhat above that of the fluid in the inlet passage 9; the movement of a chamber into communication with the grooves 53 may permit limited amounts of fluid to spray into the chamber. This spray of fluid, however, will facilitate the formation of foam within the chamber and will increase the effectiveness of the pump as a foam producing device.

When the pump is to be stopped, the flow of fluid to the inlet manifold 13 through the adapter 17 is stopped and the prime mover for rotating the pump is also stopped. Fluid entrapped within the outlet passage 11, the chambers and the inlet manifold 13 will gradually seep into the lower portion of the pump for flow through the passageway 18a and the drain port 18.

It is to be understood that the form of the invention herewith shown and described is to be taken as a preferred example of the same and that various changes in the shape, size and arrangement of parts may be resorted to without departing from the spirit of the invention or the scope of the subjoined claims.

Having thus described the invention, I claim:

1. A pump, comprising a chambered housing having a cylindrically shaped inner surface and inlet and outlet passages opening into the chamber of the housing, a rotor mounted in said housing for rotation about an axis in spaced parallel relationship with the axis of said inner surface, a plurality of vanes carried by said rotor for rotation therewith and for radial movement relative thereto to maintain the outer edges of the vanes in sliding engagement with said inner surface, and a plurality of vane retaining bars spanning each of said passages in a circumferential direction, each of said bars having its inner surface aligned with the inner surface of said housing and extending in angular relationship to the direction of movement of the outer edges of said vanes across the passage, the inner surface of said housing having grooves formed therein to extend circumferentially from the approach sides of the inlet and outlet passages, the spaces defined by said rotor, the inner surface of the housing and adjacent pairs of vanes communicating with said passages through said grooves while the spaces are approaching a position of alignment with the passages.

2. A pump, comprising a chambered housing having a cylindrically shaped inner surface and inlet and outlet passages opening into the chamber of the housing, a cylindrical rotor mounted in said housing for rotation about an axis that is eccentrically located relative to the axis of said inner surface, the eccentric relationship between said inner surface and said rotor causing the opposed faces thereof to converge in the direction of rotation of the rotor from the opening of the inlet passage to the opening of the outlet passage and to diverge from the opening of the outlet passage to the opening of the inlet passage; and a plurality of vanes carried by said rotor for rotation therewith and for radial movement relative thereto to maintain the outer edges of the vanes in sliding engagement with the inner surface of the housing, said inner surface of the housing having a groove therein extending from the opening of the inlet passage in a direction opposite the direction of rotation of said rotor to provide communication between the opening of the inlet passage and the expanding space defined by the rotor, the inner surface and an adjacent pair of vanes before the vanes are rotated to position such space in alignment with the inlet opening, said inner surface of

said housing also having a groove therein extending from the opening of said outlet passage in a direction opposite the direction of rotation of said rotor to provide communication between such opening and the contracting space defined by said rotor, the inner surface and an adjacent pair of vanes before the vanes are rotated to position such space in alignment with the outlet opening.

3. A pump as defined in claim 2 further characterized by a pair of bars spanning each of said passages in a circumferential direction, each pair of bars having the inner surfaces thereof aligned with the inner surface of said housing and symmetrically arranged in angular relationship relative to the circumferentially extending center line of their associated passage.

4. A pump, comprising a chambered housing having a cylindrically shaped inner surface and inlet and outlet passages opening into the chamber of the housing, and a vaned rotor mounted in said housing for rotation about an axis in spaced parallel relationship with the axis of said inner surface; said inner surface having grooves formed therein to extend circumferentially from the approach sides of the inlet and outlet passages, the spaces defined by said rotor, the inner surface of the housing and adjacent pairs of vanes communicating with said passages through said grooves while the spaces are approaching a position of alignment with the passages.

5. A pump, comprising a housing having a first portion chambered to form a cylindrical inner surface provided with an inlet opening and an outlet opening, said cylindrical surface being positioned with its longitudinal axis horizontal and with said inlet opening in communication with its lowest point, a vaned rotor mounted eccentrically within said cylindrical surface, a second portion of said housing formed to provide an inlet passage communicating with said inlet opening, the bottom of said inlet passage being horizontal and tangential to said lowest point of said cylindrical surface, and an inlet manifold sealingly connected to said housing in open communication with said inlet passage, the side of said inlet manifold opposite said inlet passage being formed with a liquid supply opening in substantial alignment with said inlet passage so as to form a substantially straight flow path between said liquid supply opening and said inlet opening, and the bottom portion of said manifold being formed to provide a drain port communicating with a horizontal passageway bottom aligned and communicating with said inlet passage.

6. A pump as defined in claim 5 further characterized by said inlet manifold including a top portion formed to provide an air intake opening communicating with said flow path, and by means associated with said liquid supply opening for effecting a detachable connection with a liquid supply means.
